UNITED STATES PATENT OFFICE

CHARLES F. H. BOHNHARDT, OF LYNWOOD, CALIFORNIA, ASSIGNOR TO JULIAN A. CAMPBELL, OF LONG BEACH, CALIFORNIA

OIL-TANK EXPANSION JOINT

Application filed December 5, 1928. Serial No. 324,041.

This invention relates generally to tubular expansion joint pipe connections, and is particularly concerned with a liquid seal expandable type of joint especially adapted for use 5 in oil tank structures between floating roofs and fluid delivery or sampling lines extending into the tank through the roof.

In the use of storage tanks for containing petroleum oils, it is desirable that the oil inlet 10 line to the tank open thereinto at a suitable point in the roof rather than at the bottom of the tank. This provision is made in order that should a break or leak occur in the inlet line, or should the pump for delivering oil 15 through that line become stalled, there will be no possibility of the oil contained in the tank backing out or exerting pressure in the inlet line, since the point of introduction to the tank is above the liquid level.

20 Obviously this may readily be done in a tank having a stationary roof, but difficulties are encountered when it is attempted to pump into a tank through a vertically movable roof such as various types of floating roofs commonly used. It is a purpose of my invention, therefore, to provide an expandable joint between such vertically movable roofs and a vertically extending and relatively stationary inlet line or stand pipe within the tank, such as 25 will permit relative vertical movement between the stand pipe and roof. The present joint is constructed in a manner such as to prevent not only the escape of vapors from the tank between the inlet line and the roof, but also to eliminate destructive wear between 30 parts of the joint.

The various features of the invention will be most clearly understood from the following 40 description of a typical application thereof, reference being made throughout the description to the accompanying drawings, in which

Figure 1 is a view in part section and elevation of the present joint as applied to a typical 45 tank floating roof and stand pipe structure, the roof being at its uppermost floating level and the joint parts in their corresponding positions;

Fig. 2 is a view generally similar to Fig. 1 50 but showing the floating roof at a low level

in the tank and the joint parts in an expanded position; and

Fig. 3 is an enlarged sectional view of the joint and tank parts in the position of Fig. 1.

Referring to the drawings, numeral 10 indicates a usual storage tank for containing petroleum oils, the volatility of which may range within wide limits. The tank is provided with a floating roof, generally indicated at F, the roof being adapted to float on the liquid at all times irrespective of the amount of liquid contained within the tank. The various purposes of floating roofs are well known to those familiar with the art and therefore need not be discussed herein. The roof may be of any suitable design, for instance a type such as described in my copending application on air cooled floating roofs, filed January 14, 1928, Serial No. 246,758, the roof shown therein embodying a plurality of floats or basins, suitably joined, the basins being generally similar to the floating unit 11 shown in the present drawings. Suitable means, not shown, may be provided for draining rain water from the floating roof to the bottom of the tank.

As a typical means for sealing the space between the floating roof and the tank in order to prevent the escape of vapors from the tank to the atmosphere, I have provided a liquid seal device, generally indicated at 12, this seal being similar to one described in my copending application entitled Tank roof structure, filed Dec. 5, 1928, Serial No. 324,040. The illustrated seal between the tank and roof embodies an annular trough 13, carried around the outer periphery of the roof, the inner wall 13^a of the trough being joined to the outer edge of the float unit and extending upward a considerable distance from the roof. The outer trough wall 13^b is spaced from the tank shell as at 14, there being suitable means provided for forming a seal between the trough and shell to prevent the escape of vapors from the tank to this space. An annular skirt 15, integral with the shell and depending a suitable distance from the horizontal portion 15^a, extends downwardly within trough 13, preferably to a point near its bottom when the floating roof is in its uppermost position.

Trough 13 is filled with liquid L, for instance water having a small amount of non-volatile oil on its surface to prevent evaporation. Thus a liquid seal is maintained between the floating roof and the tank shell, this liquid seal preventing the flow of vapor from space 14 or space S to the atmosphere when the roof is in its upper position.

The seal embodies in addition, an annular sheet 16 spaced from the bottom of the trough by means of feet 17. A roller 18 is mounted on the upper end of the sheet and is adapted to engage the tank wall at all positions of the floating roof, the roller instead of a sliding contact being desirable in order to eliminate friction. A pair of flexible flaps 19 of suitable composition, for instance rubber impregnated canvas, are mounted on the outer horizontal portion 16^a of the sheet, these flaps serving to engage the shell with sufficient tightness to prevent the escape of vapors from the tank into space S.

It will be seen that should considerable liquid be removed from the tank causing the floating roof to lower to an extent such that the liquid seal maintained by skirt 15 in trough 13 becomes broken, sheet 16, being submerged at its lower end in liquid L and being in engagement with the tank at its upper end through the flexible flap, forms an additional seal that is effective regardless of the position of the floating roof.

A vertical stand pipe or conduit 20 is contained within the tank, the upper end of the pipe extending through the roof, and the expansion joint embodying the invention is arranged between the stand pipe and the floating roof in order to permit vertical relative movement of the roof and conduit without undue wear of these members, and also to prevent the escape of tank vapors between the stand pipe and roof at all positions of the roof. The stand pipe rests on the bottom of the tank and is perforated at 20^a to permit the discharge of liquid into the tank by way of the stand pipe. It may be stated that in certain instances it is desirable to provide a pair of stand pipes for a single tank, each of the pipes having connection with the roof as illustrated, and to employ one stand pipe as an inlet line and the other as a sample line within which a sampling device may be lowered, suitable means being provided in this instance, of course, for readily gaining access to the interior of the standpipe at its upper end. In order for the stand pipe to be used for purposes of obtaining a representative sample of the tank contents, I have provided perforations 20^b along the pipe of suitable intervals so that the liquid in the stand pipe at any level is in direct communication with the tank liquid at that level.

The expansion joint, generally indicated at J, is seen to embody an annular liquid container or cup 21, the cup having a fluid tight

joint towards its lower end at 22, with the floating roof. The cup has a central vertical bore or opening at O, the stand pipe extending through said bore and being spaced from the inner wall 21^b as at 23. A tubular skirt 24, of somewhat larger diameter than the inner wall 21^b of the cup, is mounted upon the stand pipe at a point 25 above the upper end of the cup. The skirt extends downwardly within the cup, and is shaped at its lower end to provide an annular hook 24^b, the purpose of which will later appear. Vapor pressure beneath the cup or within space O is relieved through line 27 which communicates with the space S' in the upper interior of the skirt and leads to suitable vapor draw-off means (not shown). The cup is filled to a point near its top with suitable liquid, preferably a non-volatile oil, which, in addition to enabling the formation of a liquid seal, tends to preserve the metallic parts of the joint. It will be understood that the provision of the vapor draw-off 27 may be omitted from the structure in the event the volatility of the liquid is insufficient to warrant its inclusion.

The cup, in the position of Fig. 3, contains a plurality of concentric and tubular telescopic units 30, provided at their lower ends with hook portions 30^a extending around the units, and spaced as indicated, from the inner wall of the next surrounding unit. The upper ends of the unit are shaped to provide similar hook portions 30^b but formed inside the units, extensions 30^c being provided for purposes of forming effective liquid seals between the units when in their expanded position as will later be seen. Guide strips 32 are mounted on the hook portions of the units as indicated, the purpose of these strips being both to center each unit in relation to the adjacent units, and to insure that the vertically opposite hook portions of adjacent units will be brought into engagement when the joint assumes its expanded position as will now be described.

When the floating roof is in its uppermost position and the various members of the expansion joint are in the position illustrated in Fig. 1, a liquid seal obviously is maintained between the stand pipe and cup by virtue of the skirt depending within the liquid contained within the cup. Assuming now that liquid is drained from the tank in such amount as to cause the floating roof and cup 21 to lower to the position shown in Fig. 2, it is seen that upon downward movement of the roof, the telescopic units first lower simultaneously with the cup. Thus the hook portion on the upper end of the innermost unit becomes fitted into the hook 24^b on the lower end of the skirt, as at 35, and the remaining units depend in series from the innermost unit in a similar manner as the roof lowers. It will be seen that the annular hooks them-

5 selves have considerable depth, especially by virtue of the extension portions 30°, and therefore, in combination with an adjacent hook member, from effective liquid seals between the units. A reverse procedure follows when the floating roof raises, with the result that when it reaches its uppermost level the units are again collapsed within the cup.

10 It will be understood the drawings and description are to be considered merely as illustrative of and not restrictive on the broader claims appended hereto, for various changes in design, structure and arrangement may be made without departing from 15 the spirit and scope of said claims.

I claim:

1. In a structure of the character described, a fluid container having a top closure, a vertical conduit communicating with the interior of the container and extending through said closure, the closure being spaced from said conduit and vertically movable relative thereto, and a vertically expansible joint between the conduit and said closure, 20 said joint preventing fluid escape from the container between the conduit and top closure during their relative vertical movement.

2. In a structure of the character described, a fluid container having a top closure, a vertical conduit communicating with the interior of the container and extending through said closure, the closure being spaced from said conduit and vertically movable relative thereto, and a vertically expansible 25 joint between the conduit and said closure, said joint preventing fluid escape from the container between the conduit and top closure during their relative vertical movement.

3. In a structure of the character described, a fluid container having a top closure, a vertical conduit communicating with the interior of the container and extending through said closure, the closure being spaced from said conduit and vertically movable 30 relative thereto, and a vertically expansible liquid seal joint between the conduit and said closure, said joint preventing fluid escape from the container between the conduit and top closure during their relative vertical movement.

4. In a structure of the character described, a fluid container having a top closure, a vertical conduit communicating with the interior of the container and extending through said closure, the closure being spaced from said conduit and vertically movable 35 relative thereto, and a vertically expansible liquid seal joint between the conduit and said closure, said joint preventing fluid escape from the container between the conduit and top closure during their relative vertical movement and comprising a series of 40 telescopic members, one end member of the series being attached to the conduit and the other end member of the series being attached to the closure, and means providing a liquid seal between each two adjacent members of said series.

5. In a structure of the character described, a fluid container having a top closure, a vertical vapor conduit communicating with the interior of the container and extending through said closure, the closure being spaced from said conduit and vertically movable relative thereto, a liquid conduit 45 communicating with said container and

extending within said vapor conduit through the top closure, and an expansible joint between the vapor conduit and said closure, said joint preventing the escape of vapor from the container between the vapor conduit and top closure during their relative vertical movement.

5. In a structure of the character described, a fluid container having a top closure, a vertical conduit communicating with the interior of the container and extending through said closure, the closure being spaced from said conduit and vertically movable relative thereto, and a vertically expansible joint between the conduit and said closure, 50 said joint embodying a pair of tubular telescopic units surrounding the conduit, the inner of said units being mounted on the conduit and the outer unit having a fluid tight joint with said closure.

6. A structure of the character described embodying a liquid containing tank having a vertically movable roof, a vertical standpipe within the tank and extending through the roof and laterally spaced therefrom, and liquid seal means between the standpipe and the roof, said means embodying an annular liquid container mounted on the roof and extending around the standpipe, and a tubular skirt mounted on the standpipe and annularly spaced therefrom, said skirt depending beneath the liquid in said container.

7. A structure of the character described embodying a liquid containing tank having a vertically movable roof, a vertical standpipe within the tank and extending through the roof and laterally spaced therefrom, and liquid seal means between the standpipe and the roof, said means embodying an annular liquid containing cup mounted on the roof and extending around the standpipe, a tubular skirt mounted on the standpipe and annularly spaced therefrom, said skirt depending beneath the liquid in said cup when the roof is in its uppermost position, and a plurality of tubular telescopic units in the cup, the innermost of said units being adapted to depend from said skirt and the remaining units to depend in series from said innermost unit upon downward movement of the roof.

8. A structure of the character described embodying a liquid containing tank having a vertically movable roof, a vertical standpipe within the tank and extending through the roof and laterally spaced therefrom, a tubular skirt mounted on the standpipe and annularly spaced therefrom, the annular space between the skirt and standpipe communicating with the tank interior, an annular liquid containing cup mounted on the roof and concentric with the standpipe, said skirt depending beneath the liquid in said cup when the roof is in an upper position, a plurality of concentric tubular telescopic units in said

cup adapted to depend in series from the lower end of said skirt upon downward movement of the roof, and a vapor outlet at the upper end of the skirt for removing tank vapors by way of said annular space.

In witness that I claim the foregoing I have hereunto subscribed my name this 26th day of October, 1928.

CHARLES F. H. BOHNHARDT.
